UNITED STATES PATENT OFFICE.

LESTER J. SCHRAM, OF CHICAGO, ILLINOIS.

COLLAPSIBLE RADIATOR COVER.

Application filed August 4, 1927. Serial No. 210,614.

This invention relates to covers for radiators commonly used for heating purposes. The desirability of such covers has heretofore been known and various devices have 5 been proposed for such purposes. However, on account of the varying lengths of the radiators such covers have heretofore usually been made special or to order, and as a consequence are too expensive for general 10 commercial purposes. Such special or unitary covers are also bulky and difficult to ship or handle. In accordance with the present invention, I provide a radiator cover which may be adjusted for different sized 15 radiators and which may be collapsed so that it will require but very little room for packing or shipping.

The objects of this invention are to provide an improved radiator cover which may 20 be taken apart and folded or collapsed; to provide a radiator cover which will be pleasing in appearance and which will be securely supported on the radiator and may be 25 adjusted for different sized radiators; to provide an adjustable radiator cover with a detachable tank or water container which may be conveniently supported thereon; and to provide such other advantages and improvements as will be described in the following specification.

In the accompanying drawings illustrating this invention:

Figure 1 is a front view of the radiator cover;

Figure 2 is a bottom plan view with the humidifier removed;

Figure 3 is a perspective view of the water receptacle or humidifier;

Figure 4 is a sectional view taken on the line 4-4 of Figure 1;

Figure 5 is a sectional view taken on the line 5-5 of Figure 2;

Figure 6 is a bottom plan view of the top shown in closed position;

Figure 7 is a front view of the side portions shown in closed and collapsed position; and

Figure 8 is a top view of the parts as shown in Figure 7.

As shown in these drawings the radiator cover comprises two coacting top plates 10 and 11. The plate 10 has downwardly extending sides or side walls 12 with inwardly turned flanges 13, thereby forming a peripheral channel or bead, and the plate 11

has similar sides 14 and flanges 15 so that it may fit over and telescope with the plate 10 and its channel, as will be readily seen from Figure 1. The plates 10 and 11 are provided respectively with downwardly 60 projecting lugs or brackets 16 and 17 adjacent to the ends thereof for engagement with and supporting the end members 18 and 19 of the radiator cover. These end members are fastened to the brackets by means of 65 screws 20 and 21. The end plate 18 has a back plate 22 and a front plate 23 hinged thereto, and the end plate 19 has a similar back plate 24 and front plate 25 hinged to it. The back plate 22 has an upper bead 70 or longitudinal tubular portion 26 which fits into or telescopes with a similar bead 27 along the upper edge of the back plate 24, thereby holding these two plates in alignment throughout their range of adjustment. 75 The front plate 23 has a bead 28 which telescopes with a bead 29 on the front plate 25 which holds these parts in alignment. These upper telescoping portions or beads are enclosed in or covered by the channel 80 around the top, as will be readily seen from Figure 4.

The back plate 22 has a hook 30 for supporting the water receptacle or humidifier 31. The back wall of this humidifier has 85 hooks 32 which project at one side thereof and a longitudinal hook or engaging piece 33 which projects at the opposite side thereof so that the position of the receptacle may be reversed with respect to the cover if desired.

When the cover is to be applied to a radiator, the parts are all assembled in the manner indicated, and as the entire end sections or portions of the cover are arranged 95 so that they will telescope with each other, they may be adjusted for different lengths of radiators. When the cover is taken apart, as for packing or shipping, the end plates 18 and 19 are disconnected by unscrewing the screws and the ends and front and back members may be swung or folded together, as shown in Figure 8. The top may also be collapsed or slid together, as shown in Figure 6, so that the entire radiator cover may be packaged in a substantially flat thin package. This is an exceedingly important feature in connection with the sale of such articles, as they may be displayed in a store in their normal adjusted 100 105 110

position, and the cover may be delivered to the purchaser in a flat package which may be easily carried or a number of such covers may be wrapped together as they are comparatively light and readily handled.

- From this description, it will be seen that I provide a radiator cover which is of pleasing appearance and which readily lends itself to artistic decoration, as for instance, 10 to make the top portion simulate a stone slab or board with the metallic depending portions ornamented or decorated in a different manner. Furthermore, the radiator cover will fit closely over the radiator and 15 will be securely supported thereon so that the top will serve for holding various articles. It will also be noted that changes may be made in the details of construction and arrangement of the parts without departing 20 from the spirit of this invention; therefore I do not wish to be limited to the exact arrangement herein shown and described, except as specified in the following claims, in which I claim:
- 25 1. In a radiator cover, the combination of a telescoping top member, telescoping front and back members, end members hinged to the front and back members, and means for

detachably securing the end members to the top members.

2. The combination of a radiator top, comprising two plates having telescoping peripheral channels, brackets secured to said plates, ends, screws for securing the ends to the brackets, back plates hinged to the ends 30 and having telescoping beads at the top thereof, and front plates also hinged to the ends and having telescoping beads at the top thereof.

3. A radiator cover, comprising a top 40 plate having a peripheral channel, a second top plate engaging with the first plate and having a peripheral channel adapted to telescope with the first named channel, brackets secured to said plates, end plates engaging with said brackets, screws for securing the end plates, to the brackets, front plates hinged to the end plates, said front plates having telescoping beads for holding them in alignment, and back plates hinged to the 45 end plates, said back plates also having telescoping beads for holding them in alignment, the beads of the front and back plates being enclosed in the charnels of the top plates when the parts are assembled.

LESTER J. SCHRAM.
